UNITED STATES PATENT OFFICE.

JAMES J. SULLIVAN, OF BROOKLYN, NEW YORK.

SPOOL-HOLDER.

1,189,635.

Specification of Letters Patent. Patented July 4, 1916.

Application filed November 20, 1915. Serial No. 62,517.

To all whom it may concern:

Be it known that I, JAMES J. SULLIVAN, a citizen of the United States, and residing at Brooklyn, in the county of Kings and State of New York, have invented certain new and useful Improvements in Spool-Holders, of which the following is a specification, such as will enable those skilled in the art to which it appertains to make and use the same.

This invention relates to devices for holding spools of thread, and the object thereof is to provide an improved device of this class designed for use by ladies when sewing and which is adapted to be detachably connected with the front of a body garment so as to hold a spool of thread in a convenient position for use.

The invention is fully disclosed in the following specification, of which the accompanying drawing forms a part, in which the separate parts of my improvement are designated by suitable reference characters in each of the views, and in which:

Figure 1 is a side view of my improved spool holder and showing a spool of thread mounted thereon; Fig. 2 a front view but showing the parts in a different position; Fig. 3 a plan view of a blank of sheet metal from which a part of the spool holder shown in Fig. 1 is made; and Fig. 4 a view of another part of said holder.

In the practice of my invention, as shown in the drawing, I provide a back plate a formed from a blank a^2 , shown in Fig. 3, bent at one end to form a right angled arm a^3 provided at the free end, and in one edge portion thereof, with a transverse recess a^4 partially closed by a hook-shaped finger a^5 . I also provide a finger piece b which is also formed from a blank b^2 shown in Fig. 4, said blank being provided at one end with a right-angled ear piece b^3 which is placed on and pivoted to the end portion a^6 of the back plate a , as clearly shown at a^7 , and the other end portion of the blank b^2 is formed into the finger b which is bent at right angles to said blank, as clearly shown in Fig. 1, and the free end of which is adapted to be forced into the recess a^4 where it is normally held by the finger a^5 .

The back plate a is preferably stamped

to form an ornament a^8 , and said back plate is provided at the back thereof with a pin c whereby the spool holder may be connected with the front body portion of a garment, and in the use of this device the finger b is detached from the recess a^4 and turned on its pivot at a^7 in order to permit of a spool d being slipped onto said finger, after which said finger is swung into the position shown in Fig. 1 and forced into the recess a^4 where it is held by the spring action thereof until forcibly released in order to detach the spool d .

This device may be used whenever such devices are required, and my invention is not limited to any particular form of the pin c nor to any method of connecting it with the back plate a , nor to the other details in form and construction shown and described, and various changes herein and modifications thereof may be made, within the scope of the appended claims, without departing from the spirit of my invention or sacrificing its advantages.

Having fully described my invention, what I claim as new and desire to secure by Letters Patent, is:

A spool holder composed of two sheet metal parts one of which forms a back for the holder and is provided with a top part which projects at right angles thereto and the other of which constitutes the spool support and comprises a bottom part which projects at right angles to the back of the holder and is provided with an upwardly directed finger member adapted to be connected with the top part which projects from the back of the holder, said bottom part being also provided with a vertical member pivotally connected with the back of the holder whereby said finger member is rotatable in a plane parallel with the back of the holder.

In testimony that I claim the foregoing as my invention I have signed my name in presence of the subscribing witnesses this 18th day of November, 1915.

JAMES J. SULLIVAN.

Witnesses:

C. MULREAMY,
H. E. THOMPSON.
